UNITED STATES PATENT OFFICE

SAUL SHALER, OF NEW YORK, N. Y., ASSIGNOR TO THE ELECTRIC SAFETY RAZOR CORPORATION OF AMERICA, OF NEW YORK, N. Y., A CORPORATION OF NEW YORK

ELECTRIC CORD CONNECTER

Application filed June 2, 1924, Serial No. 717,230. Renewed March 11, 1929.

This invention relates to connectors for use in conveniently making and interrupting, at will, electrical connection between parts of an electric circuit, for instance, in bringing the end of a flexible cord into electrical connection with terminals, and particularly to electrical connectors of the plug and socket type, or type in which two members are assembled by telescopic action.

10 The object of the invention is to provide a connector which will be simple and cheap in construction and assembly, but very efficient and durable under the usage to which devices of this kind are subjected in service.

15 According to one part of the invention, the pairs of terminals with which the respective members of the connector are equipped, are so mounted in the telescoping members that, while permitted to enter into sliding contact 20 with one another in the assembly of the connector, they are nevertheless sufficiently re-tired within the members that carry them to prevent either electrical or physical contact with other objects, when the members are 25 apart.

According to another part of the invention, terminals are mounted in the member which carries them by introducing them into longitudinal bores or openings in the body of such 30 member, and then screwing a shell or cap upon the end of said body portion to prevent escape of the terminals from the bores; the terminals being preferably provided with lateral projections or ears which are gripped 35 between the end of the body portion and the shell, so as to prevent displacement of the terminals in either longitudinal direction.

According to another part of the invention, the flexible conductors or members of the cord 40 are secured to one member of the connector through means of an anchoring tongue so that the ends of said conductors, which are soldered or otherwise united with the terminals within the members, would not be subjected to 45 impairment by a pull upon the cord; said anchoring tongue being constructed with a series of apertures through which the conductors are woven, preferably in opposite directions, so that when drawn taut they develop 50 a grip upon the bars between the apertures

and so relieve their connections with the terminals; and said anchoring tongue being preferably combined with that of the connector members which comprises the body portion and shell, and being held in place by 55 seating it in a recess in the body portion and confining it in said recess by engagement of the shell.

In the accompanying drawing, in which the preferred embodiment of the invention is 60 shown by way of illustration—

Figures 1 and 2 are sectional views in planes at right angles to each other, showing a connector embodying the several features 65 of the invention.

Figures 3 and 4 are, respectively, a side elevation and an end view of the plug member of the connector which carries the flexible cord; and

Figure 5 is a detail view of one of the 70 terminals.

1 represents the socket member of an electrical connector, in which are mounted terminals 2, 2^a, which, in the arrangement shown, are of knife blade form and, by way of illustrating a use for the connector, are shown as leading to members of a make and break device 3 which forms no part of the present invention. Socket member 1 has a barrel portion 4 extending therefrom an axial distance 75 sufficient to surround and form a guard for the terminals 2, 2^a but without obstructing access to said terminals by terminals mounted in the other member to be assembled therewith. 5 represents the coaxing member of 80 the connector which will be herein termed the plug member, and which comprises a shell 5^a and a body portion 6 secured in said shell by means of threads 7. Within the body portion 6 are terminals 8, 8^a, mounted therein by 85 inserting them in bores 9, 9^a located to present them in positions to receive the blade terminals 2, 2^a when the members of the connector are assembled. Terminals 8, 8^a are bifurcated or in the form of clips that receive 90 the blade terminals between their jaws, and in order to facilitate entry of the blade terminals they have deflected outer ends 8^b. They are preferably made by bending a piece of 95 metal upon itself as shown in Figure 5, the 100

bent portion being extended laterally in opposite directions as shown at 8^b, to provide an enlargement through which the terminal engages the end of the body portion surrounding the bore which receives the terminal, as well as the shoulder of the shell by which said enlargement is pressed firmly to its seat against the body portion. Resiliency of the clip terminals 8, 8^a together with the impingement of their shoulders 8^y against the sides of the bores in which they are mounted, cause said terminals to enter into effective contact with one another, the reduced width of the terminal beyond their said shoulders, allowing sufficient resiliency for this purpose. To secure the terminals 8, 8^a in their bores 9, 9^a, said terminals are constructed with lateral extensions or ears 8^b which overlie the end of the body portion 6 and are confined thereagainst by means of an annular shoulder 10 on the shell 5^a.

Conductors 11 constituting the flexible cord, have their ends electrically united with the terminals 8, 8^a, preferably by soldering or otherwise connecting them with the ears 8^b, and in order that an excessive pull on the cord 11 may not impair these connections, an anchoring tongue 12 is seated in a groove 12^a in the end of the body portion 6, and held therein by engagement of the annular shoulder 10 with the offsets 12^b of said tongue; and said tongue is constructed with apertures 13, 14 through which the wires 11 can be woven, preferably in opposite directions, so that tension upon the cord will cause the wires to bind against the bars which define the apertures and thus save the electrical connections from injury.

In assembling the parts of a connector constructed as herein described, it is simply necessary to unscrew the shell 5^a from the body portion 6 of the plug member of the connector, thread the cord 11 through the end opening of said shell, pass the shell back upon the cord where it will not inconvenience manipulation of the wires of the cord, then weave the wires through the apertures of the anchoring tongue and electrically connect the ends of said wires to the clips 8, 8^a, when the shell can be returned to and screwed home upon the body portion, and the assembly will be complete and an end of the body portion 6 will be left protruding for insertion into the socket member 4.

55 I claim:

1. A connecting member for electric circuits, comprising a body portion having a transverse slot in an intermediate portion of one end and longitudinal bores on either side of said slot, terminals fitted in said bores and having lateral extensions overlying the end of said body portion, an anchoring tongue consisting of a flat plate having an offset end seated in said recess, and a shell threaded upon said body portion and constructed with

an annular shoulder engaging with and holding against the body portion the offset end of the anchoring tongue and the lateral extensions of the terminals.

2. In a connecting member for electric circuits, a body portion having a longitudinal bore to receive a terminal, a bifurcated terminal consisting of a piece of metal bent upon itself and having its bent portion fashioned to provide a wire-receiving trough and extended laterally to provide an enlargement, said terminal fitting in said bore and engaging the body portion around the bore by means of its said enlargement, and a shell secured upon the body portion and engaging said enlargement to confine it in said bore.

Signed at New York, New York, this 28th day of May, 1924.

SAUL SHALER.
